PROCESS OF REFINING OILS

William Thornhill Hancock, Long Beach, Calif.

Application September 23, 1935, Serial No. 41,676

2 Claims. (CL 196—147)

This invention relates to improvements in treating hydrocarbon oils and/or distillates thereof to produce oils of enhanced stability with regard to color and of decreased sulphur and 5 gum content.

The principal object of the invention is to treat petroleum distillates, particularly cracked distillates, either in liquid or vapor phase, by contact with a solid adsorptive material which may or 10 may not have catalytic properties while in the presence of carbon dioxide.

The invention of thus contacting hydrocarbons may be practiced under superatmospheric pressure while the hydrocarbons are suitably heated 15 to a temperature sufficient for their vaporization either before or after such contact treatment, but said temperature is below the cracking temperature of the hydrocarbons.

Heretofore in the treatment of cracked distillates derived from the cracking of oils of California origin, the so-called Gray vapor phase refining process, as illustrated in U. S. Patent 1,340,889 and others, has not been successful in that from observations not only is it found that 25 the gums or polymerized products of refining are not reduced, but they are actually increased. In addition, by the application of the above so-called Gray process to California cracked distillates of relatively high sulphur content, no reduction 30 in sulphur occurs so that the distillates still have to be sulphuric acid treated to reduce such sulphur. As the acid treatment will also remove gums (sulphuric acid being a polymerizing agent), it is clearly no advantage to use the 35 so-called Gray process on cracked distillates of California origin.

In the Mid-Continent oil fields where relatively high sulphur content oils are not common, the so-called Gray process is used to polymerize 40 undesired unsaturates so that color stability is assured without subsequent treatment with sulphuric acid.

It is, therefore, a further object of this invention to provide a treatment for petroleum and/or 45 its distillates, whether cracked or not, but particularly for cracked distillates of California origin, whereby undesirable constituents thereof tending to render the treated product of unstable color are converted and removed from the oil under treatment, either by polymerization or otherwise, and at the same time the sulphur content is materially reduced. This may be accomplished either in the liquid phase or vapor phase, by contacting the oil, whether cracked or 50 not, with an adsorptive material of the type of

fuller's earth while in the presence of carbon dioxide which may be derived from the adsorptive material itself under suitable heat conditions, or may be an addition product such as flue gases or the like. 5

A diagrammatic flow sheet is furnished which may be used to illustrate the process both in the liquid and vapor phases.

Example 1 describes liquid phase treatment in which, merely by way of illustration and not of limitation, a cracked distillate of California origin such as cracked distillate of gasoline boiling range is drawn from storage 10 by pump 11 and forced through a pipe coil 12 in furnace 13 whereby it is heated by burner 14 to a temperature sufficient for the purpose, from about 300° F. to 500° F., below the cracking temperature of the distillate, and passes through lines 15 and 16 into the lower part of a treating tower 17, containing a body of adsorptive material 18 held 20 between upper and lower perforated plates or screens 19 and 20, respectively, which are of well known construction to permit relatively free flow of liquids or vapors, while preventing carrying over of the adsorptive material. 25

The adsorptive material may be any of the well known polymerizing, decolorizing, and adsorptive clays, such as fuller's earth, bentonite, Death Valley clay, Muroc clay, or the like, which may have catalytic properties as well as being 30 conducive to hydrogenation, depending on constituents thereof under operating conditions, and the hydrocarbon liquid is passed upwardly there-through concurrently with a stream of carbon dioxide, or a mixture of gases containing carbon dioxide, such as flue gases, drawn, for instance, from furnace 13 through line 21 and forced by pump 22 into lines 15 and 16 to be intermingled with the heated oil and pass through the adsorptive material 18. 35

The carbon dioxide, or mixture containing carbon dioxide, may be introduced into the heated oil as a cooled gas or at about the same temperature as the oil and a heat exchanger 23 is provided in line 21 to suitably heat or cool the CO₂ gas supplied from furnace 13 or from any other source such as through line 24, and the volume of CO₂ so introduced to the oil may be varied by simple trial to effect maximum refining of the 50 oil depending on the type of oil under treatment. Flue gases containing about from 5% to 15% of CO₂ and about 10% of oxygen have been found satisfactory. Steam may be concurrently introduced through line 24. 55

The pressure maintained on the liquid oil while being heated and treated with the adsorptive material and CO₂ may be varied by the setting of a valve 25 to range between 50 and 200 pounds per square inch, and is preferably about 100 pounds, so that upon reduction of such pressure, to say from about 30 to 50 pounds, certain desired low boiling fractions will be released upon expansion through lines 26 and 27 into fractionating column 28 whence the desired distillate of definite boiling range, such, for instance, as gasoline, will pass through line 29 into condenser 30 and receiver 31.

Undesired heavy fractions, including converted and/or polymerized products, will be drawn from column 28 through draw-off line 32, while incondensable gases including any excess CO₂ will be drawn off from receiver 31 through line 33, and the gasoline and any water will be drawn off 20 respectively through lines 34 and 35.

The pressure maintained on the oil in treating tower 17 during operation is preferably such as will prevent substantial vaporization at the operating temperatures in liquid phase treatment, 25 and tower 17 may be suitably insulated or lagged to prevent great heat losses.

The flow of liquid hydrocarbon through tower 17 may be downward as well, but in liquid phase treatment an upward flow is desired to prevent 30 or minimize gas binding in the adsorptive material.

The adsorptive material used may be any one of a number containing varying percentages of SiO₂, Al₂O₃, CaO, MgO, Na₂O, K₂O, Fe₂O₃ of the 35 general class of materials used for so-called contact clay refining either in liquid or vapor phase, provided such refining takes place in the presence of carbon dioxide.

What the exact chemical reactions are is not 40 fully known but an improved product is produced over that known by ordinary liquid or vapor phase clay refining having an increased color stability and reduced sulphur content.

While the CO₂ may be introduced to the contact material with the oil in many modifications 45 apparent to those skilled in the art, it may be desirable under certain conditions of material supply to use an adsorptive material containing CO₂ which is released in the treating tower 17 50 under suitable conditions of temperature and pressure.

For instance, it has been found that a mineral having the following chemical analysis is suitable for the herein disclosed process:

	Percent
SiO ₂	18.44
Fe ₂ O ₃	1.28
Al ₂ O ₃	6.58
CaO	37.35
MgO	1.94
Na ₂ O	0.96
K ₂ O	0.22
CO ₂	29.31
Moisture	3.84

65 It is not known in what form the CO₂ is held in the above mixture, or whether all of it is released, but it is believed that part of it at least may be held as MgCO₃ which is known to yield CO₂ at a temperature of about 390° F. in the presence of SiO₂ which is within the range of temperature of the liquid hydrocarbon under treatment in tower 17 and which preferably varies between 300 and 500° F.

70 75 It is found, however, that in the presence of

CO₂ improved results are obtained, as above described.

In Example 2, pipe coil 12 may be considered as a cracking coil for liquid hydrocarbons in which a cracking temperature of about from 700 to 900° 5 F. may be applied to the oil. In this case, the cracked oil is preferably passed through a line 36 into a vaporizing drum 37, wherein certain tarry heavy fractions are removed, the vapors then going into a fractionating column 38 similar to 10 column 28 where they are cut to a desired boiling range and then passed through line 39 downwardly through the contact in tower 17 in the presence of CO₂ introduced through lines 21 and 15 as before.

In this case the temperatures and pressures in tower 17 will be the same as before stated, and liquid polymers, oxidized products, and the like may be continuously drawn off through pipe 40.

Such vapor phase refining of cracked or other material may be conducted by passing the vapors and CO₂ upwardly through the adsorptive material, and suitable valves, which may be automatic or manually controlled, are placed throughout the system as indicated to regulate the temperature, 20 pressure, rate of flow, etc., as required, to maintain continuous operation in well known fashion.

In liquid phase refining of cracked California distillates when using a local California clay, known as "Muroc" treated clay, which shows the 30 following analysis:

	Percent
SiO ₂	58.14
Al ₂ O ₃	16.04
Fe ₂ O ₃	1.76
CaO	1.70
MgO	2.95
Na ₂ O	1.40
K ₂ O	0.63
Loss on ignition	17.50
	40
	100.12

in tower 17, the use of flue gases at the rate of about two (2) cubic feet per barrel of cracked 45 distillate throughput per hour (said flue gases including about 10% CO₂ and 10% O) has proved effective with a small amount of added steam through pipe 24 to reduce the gum content of the finished gasoline to 2 milligrams per 100 cubic centimeters, whereas the same distillate when 50 passed through the same Muroc clay without the flue gases contains 176 milligrams per 100 c. c. Under the same comparative conditions the gravity (A. P. I.) was increased from 55.70 to 63.8°, 55 the color from 3 N. P. A. to 30+, the octane rating (C. F. R.) from 65 to 71, the initial boiling point lowered from 100° F. to 93° F., the end point lowered from 485° F. to 354° F., and the residual sulphur lowered from 0.720 to 0.464.

60 Combined with the above results in obtaining a treated gasoline of stable color and superior quality is the fact that the total amount of steam used seems to have been absorbed or converted in the final product, inasmuch as substantially 65 no water appears in the final product.

As before stated, the full theory of the chemical reactions taking place is not fully comprehended but it might seem that the clay exercises some catalytic effect in combining the CO₂ and/or the 70 O and/or the steam in the treating tower to produce the new product.

That some conversion seemingly takes place in the clay is indicated by the fact that about five percent (5%) of a dark colored liquid may be 75

continuously, or semi-continuously; drawn off through valve 40 even when liquid phase refining is conducted as described. This liquid has a gravity of about 26° when compared with about 5 56° of the introduced distillate.

It is, of course, obvious that the flue gases and/or steam may be separately directly introduced into the treating tower below the screen 20 with the heated oil which may be supplied 10 directly from the condenser of any well known cracking system. In general, the use of flue gases may be varied from about 2 to 20 cubic feet per barrel of oil treated and such rates may be changed to meet the requirements of any particular stock treated.

I claim as my invention:

1. In the process of refining oils wherein a stream of cracked gasoline distillate is passed in

liquid form through a body of adsorptive material at a temperature of between 300° and about 500° F. while under a superatmospheric pressure sufficient to maintain said liquid form, the step which comprises: simultaneously passing a stream 5 of flue gases containing free oxygen through said material with said oil.

2. In the process of refining oils wherein a stream of cracked gasoline distillate is passed in 10 liquid form through a body of adsorptive material at a temperature between 300° F. and about 500° F. while under a superatmospheric pressure sufficient to maintain said liquid form, the step which comprises: simultaneously passing a stream 15 of flue gases containing free oxygen and steam through said material with said oil.

WILLIAM THORNHILL HANCOCK.
